UNITED STATES PATENT OFFICE.

CORNELIUS N. HORTON, OF PEEKSKILL, NEW YORK, ASSIGNOR TO
S. FLETCHER ALLEN, OF SAME PLACE.

BRICK-MACHINE.

SPECIFICATION forming part of Letters Patent No. 349,395, dated September 21, 1886.

Application filed March 9, 1885. Serial No. 158,280. (No model.)

To all whom it may concern:

Be it known that I, CORNELIUS N. HORTON, a citizen of the United States, residing at Peekskill, in the county of Westchester and State 5 of New York, have invented certain Improvement in Brick-Machines, of which the following is a specification.

My invention consists of improvements upon a machine that has long been in use and 10 has many merits as a horse-power machine; but attempts heretofore made to adapt it to steam-power have proved failures; and the object of my invention is to overcome those 15 defects that have prevented its being an acceptable steam-power machine.

The reason why steam cannot always be applied to a machine that will perform well with horse-power is that obstructions that will cause a horse to stop in its travels with the 20 sweep will, with steam-power, cause a breakage of some part of the machine, since the steam-power applied usually far exceeds that of the horses used, and cannot be either controlled or trained as can the horses.

25 I attain my object by means set forth in the following drawings, in which similar letters refer to similar parts throughout the several views.

Figure 1 is a side elevation of a brick-machine, showing the application of my improvements. Fig. 2 is a side view of my haul-out-tripping mechanism. Fig. 3 is an edge view of a connecting-rod. Fig. 4 is an edge view of the connecting-rod used in the haul-out 30 combination, and Figs. 5 and 6 relate to improvements in my haul-out mechanism.

A represents the mud-shaft of the machine, and stands in the center of the square box E, of which A' A' constitute two of the corner 40 framing-timbers, and A'' is the plank bottom of said box, resting on cross-timbers A''' between the corner timbers. Crown-wheel B imparts motion through pinion C to the cam D. Wipers on the lower end of the mud-shaft 45 force the clay from the box E into the iron chamber F, which is secured to the front of the machine, and of which the drawings give an end view. A plunger moves up and down in this chamber, actuated by the connecting- 50 bar a. During the descent of this plunger a

mold rests beneath the chamber on the rollers c e and just fills the space there shown.

Bar a is connected by its lower end to a cam, b, on the square shaft, one end of which shaft is shown at e. Upon this same shaft the 55 pressure-lever G is secured. This lever I construct substantially as shown. Heretofore the slot x was made so short that the machine could not be entirely stopped delivering clay unless the machine was stopped. The notches 60 1, 2, and 3 shown near the base of this slot are designed to receive a pin that passes through the bifurcated end of the long pitman H. This pitman is connected at its upper end with a crank-pin, j, in cam D, and extends downward on both sides of lever G, as may be seen in Fig. 3, and as the cam or crank lifts the pitman H the extent of the throw of lever G will depend upon the notch in said lever, whether in 1, 2, or 3, with which pin 70 v in pitman H engages. If with notch 1, of course the movement of G will be less than if engaged in 3—the notch where it is now shown to be caught. It will be plainly seen that the upward movement of G will cause a 75 reverse movement of cam b, and a consequent downward movement of the plunger in chamber F, which fills the mold below with clay, so it will be seen that the varying movements given to G varies the amount of pressure upon 80 the clay in the mold, thus adapting the pressure to the temper of the clay.

After the mold is filled it must be pushed forward from beneath chamber F to the platform f. While this mold is being filled an 85 empty mold is inserted from the opposite side of the machine from that represented in the figure, just back of the filled mold and forward of a bar which operates upon a rock-shaft. Rod i is connected at one end with this bar inside of the machine, and outside with arm h, which is secured to shaft k, and is supported on bearings secured to the front corner timbers, one end of a journal-box being visible at l. Secured to this shaft, also, is the lever m, which 90 may be traced by dotted lines to its connection with rod n. The upper end of rod n is connected to the lever j. This lever is pivoted at o, and has its outer end hinged to connecting-rod K, which is hinged at its upper end with 95 100

lever L. This lever is pivoted at one end at q, and has a bearing, r, at its other end, which admits of free movement up and down only. About midway between the ends of this lever 5 I place a friction-roller, s, calculated to engage with cam D.

Now, when a mold is filled with clay and an empty mold is in place, cam D operates to depress the lever L, which, through K, depresses 10 one end of J, lifting its other end and rod n and the lever m, which throws h forward, and i, with the bar at the inner end, pulls forward the empty mold, driving the follower ahead of it to the platform f, when cam D, receding, 15 permits these parts to fall back ready for the next mold. As a counterbalance, and to aid the several parts to resume a normal position of rest, a weight, v, is attached to rod n. If, now, an obstruction—such as a stone—has 20 found its way into the mold to prevent its removal, the undue pressure will automatically trip the haul-out combination. The center of fulcrum o should be a trifle to the right of the center of shaft 7, when any unusual pressure 25 upon K will overcome the counterbalancing-weight W, causing it to ascend against the stop 9, as hereinafter described. Lever 4 is attached to weight W, which in turn is secured to arm 5, which is secured to an angle-iron, 6. 30 This angle-iron may be traced by the dotted outlines. It is pivoted on shaft 7, and has an arm, 8, extending upward, and this arm carries the pivot or fulcrum on which lever J is suspended. 7 has a bearing, 2', next the 35 framing of the machine, as will be seen by reference to Fig. 2, and also an outer bearing, 2''. This outer bearing has an upward extension, 2''', the object of which is to form an outer support for pivot o, as shown in Figs. 1 and 2. To 40 give a firm foundation to 2' and 2''', I extend the plank foundation to 2' and 2'''. I extend the plank bottom of box E, as at A', and brace it with brackets 3' and 3''. It will now be seen what effect is produced by throwing up the lever 45 when an obstruction prevents the delivery of a mold. Weight W falls against the stop 9, and pivot o describes the arc indicated by dotted line 10. This lowering of fulcrum o has the effect of lowering lever L beyond the reach 50 of cam D, and the haul-out becomes inoperative. Pulling weight W back to its stop 4' restores the combination to normal position again. When the haul-out is stopped, it is of course important to stop the further discharge 55 of clay from chamber F. This is effected by releasing pitman H from its hold on lever G, which operation I will now describe.

By reference to Fig. 3, which is a top view of G and the levers it supports, except x', which 60 is not here shown, it will be seen that lever 1' is divided at its lower end, so as to find a bearing on each side of G, while its upper end projects through and beyond the top edge of the likewise forked lever 1''. A pin passes 65 through 1' at 1'', and by means of this pin this lever is connected to pitman H at t by connecting-bar t'. Another pin, u, through 1' is

adapted to catch in notches in the under faces of lever 1''. Lever 1' is extended into a hand-bar toward the front of the machine, and has 70 its other end pivoted to an extension of G at w. Now, it will be obvious that if lever 1'' be raised from the position now shown pin u will be released and the weight of the pitman H will cause it to fall back from its engagement 75 with notch 3, and, instead of lifting the lever, pin v will travel in the slot x, and hence operation of the press will cease.

Lever x' (which is not shown in Fig. 3, to avoid confusion, but is shown in Fig. 1) is pivoted to the outer end of lever 1' at one end, and its other end is made circling for a good hand-hold, and has an eye which slides over the small end of lever 1''. If the present position of pin v of pitman H should require to 80 be changed from notch 3 to notch 2 or 1, it can be done without stopping any part of the machine by simply grasping x', lifting it to free 1'' from pin u, and by pulling it forward draw v into the desired notch, and by dropping this 85 lever on pin u again the change has been accomplished. So, after the pressing mechanism has been stopped, it can be at once set in motion by lifting and pulling forward lever x'; but to insure the engagement of pitman H and 90 lever G at a time when no mischief can ensue, a safeguard is provided. Connecting-bar t' is 95 furnished with a projection, y, and the lever G with a curved projection, y'. When v of pitman H is traversing slot x, this projection y travels 100 within the arc provided by y', and cannot be brought forward until v arrives at the point for approaching the notches 1 2 3.

My method of making connecting-rod K is set forth in detail in Fig. 4, in which B' is an 105 edge view, and B² a cross-section through line b'. I make the rod in two pieces, the half b'' at its jointed end being provided with short flanges beveled at the inner edges to receive the correspondingly-beveled part of b'', as shown 110 more clearly at b'''. By using this flange I am enabled to use a single bolt to secure the two halves together. At c' is shown a slot formed 115 for the reception of a wedge-like key, as seen in Fig. 1, by which the length of the rod may be varied to the fraction of an inch.

I wish now to refer to the rod i of the haul-out combination. The old method of making this rod is shown at Fig. 6, in which i' is the bar operating back of the molds, and which is 120 carried upon arms similar to h, Fig. 5. Through this bar an eyebolt, j, was inserted, as shown, provided with a nut and long thread for adjustment of length of bar i. Then by means of a chain-link, k, and an eye on the end of the 125 bar the connection was complete, as shown. The result was a combination constantly wearing and stretching. Fig. 5 will show how I attach the bar i by an eye directly to a pin in h', and then by a long nut and right and left 130 hand threads on the two inner parts of the rods I have a rod that is firm and adjustable at any time from the front of the machine.

As constructed heretofore, bar d has been

suspended between chamber F and post A'. Located here, they were often bent by having displaced molds thrust against them. By setting the chamber a little farther outward on the frame, I bring the bar d directly in front of post A, thus removing it from all liability to damage. A similar bar acts upon the opposite side of the machine. To avoid setting chamber F inconveniently far forward, I mortise out A' a trifle to accommodate bar d, as shown by the dotted line at the upper end of the bar.

Having fully described my invention, what I claim, and desire to secure by Letters Patent, is—

1. The combination, in a brick-machine pressing mechanism, as described, of the levers G, 1', 1², and x', pitman H, and rod t, united and operating together substantially in the manner described.

2. The pitman H and rod t, provided with

arm y, combined and operating, as described, with levers 1' 1² x' and the cam G, provided with projection y'.

3. In a brick-machine press-tripping mechanism, the combination, substantially as shown, of the bifurcated lever 1', pin u, notched lever 1², and hand-lever x'.

4. In a brick-machine haul-out, the combination of cam D, roller s, lever L, connecting-rod K, lever J, rod n, lever m, arm h, and rod i, united and operating substantially as set forth.

5. In a brick-machine haul-out-tripping mechanism, the combination of angle-iron 6, fulcrum o, pivot 7, standards 2", arm 2'', lever 5, weight W, lever 4, and stops 4' and 9, combined and operating substantially as shown.

CORNELIUS N. HORTON.
